UNITED STATES PATENT OFFICE.

LAURENTE RUPP, OF MONTREAL, QUEBEC, CANADA.

FLESHING APPARATUS.

No. 882,270.

Specification of Letters Patent. Patented March 17, 1908.

Application filed November 23, 1906. Serial No. 344,696.

To all whom it may concern:

Be it known that I, LAURENTE RUPP, a citizen of the United States of America, residing at the city and district of Montreal, in the Province of Quebec, Canada, have invented certain new and useful Improvements in Fleshing Apparatus; and I do hereby declare that the following is a full, clear, and exact description of the invention, such as 10 will enable others skilled in the art to which it appertains to make and use the same.

My invention relates to fleshing knives for use in tanning operations; the object of my invention is to provide an efficient, rotary fleshing knife of few parts; a further object 15 of my invention is to provide means for adjusting the movable parts of the knife; and, my invention consists of the construction, combination and arrangement of parts as 20 herein illustrated, described and claimed.

In the accompanying drawings, forming part of this application, I have illustrated one form of embodiment of my invention, in which drawings similar reference characters 25 designate corresponding parts, and in which:

Figure 1 is a side elevation, partly in section; Fig. 2 is an elevation of a guard plate, looking from the outside; and, Fig. 3 is a vertical section through the knife showing 30 its actuating shaft in elevation.

Referring to the drawings, 1 designates a base plate, on which is secured a pedestal 2, having a bifurcated upper end provided with bearings 3. Disposed in the bearings 3 is a 35 shaft 4, on which is disposed a loose pulley 5, and on which is secured a fixed pulley 6.

Secured on the base plate 1, adjacent the pedestal 2, is a second pedestal 7, bearing a plate 8 provided with a slot 9. Disposed on 40 the plate 8 is a circular casing 10, having a beveled edge 10^a at one end, and adjustably maintained on the plate 8 by means of the set screw 11.

Carried by the free end of the shaft 4 is a 45 circular knife 12, provided with a beveled cutting edge 13, which projects slightly forward of the beveled edge 10^a of the casing 10. By means of the set screw 11 and the slot 9, the casing 10 may be set to vary the 50 projection of the cutting edge of the knife 12.

Disposed on the plate 8 is a bracket 14, adjustably maintained in position by means of the set screw 15 working in the slot 15^a, and projecting into the plate 8. Carried by 55 the upper end of the bracket 14 is a set screw 16, projecting through a slot 17 provided in

the guard plate 18, the inner face of which is parallel to the cutting edge 13 of the rotary knife 12.

The inner edge of the guard plate is 60 beveled at 19, and the outer portion of the guard plate is provided with the projecting flange 20. The bracket may be adjusted to varying distances from the cutting edge 13 of the knife, so as to vary the depth of the 65 cut thereof.

Secured to the guard plate 18, is a segmental guide 24, having a rounded projecting edge 25. The guide 24 is provided with slots 26, to receive securing bolts 27, working into 70 the plate 18. Space bolts 28 in the plate 18 serve to abut against the plate 24 and space the same from the guard plate 18.

The object of the guide 24 is to prevent the cutting of the hide treated, and to provide 75 means for discharging the hair and other particles into the knife 12.

Disposed over the pedestal 2 is a hood 21, provided with openings 22 for the passage of a suitable driving belt for the pulleys 5 and 6. 80

In the operation of the invention, the skin to be fleshed is passed over the cutting edge 13 of the knife bearing on the guard plate on one side, and the beveled edge 10^a of the casing on the other side. The matter cut 85 from the skin is forced out of the casing 10 by the rotary movement of the knife.

The connection between the shaft 4 and the knife 12 is made by means of a spider 23 to permit the passage of this matter, and the 90 guard plate 18 does not extend to the bottom of the casing 10 for the same purpose.

Having thus fully described my invention, what I claim as new, and desire to secure by Letters Patent, is:—

1. A fleshing knife comprising the combination of a rotary blade, a shaft secured to the blade, a pedestal supporting the shaft, loose and fixed pulleys on the shaft, and a hood disposed over the pedestal and the pulleys and provided with belt openings. 95

2. A fleshing knife comprising the combination of a rotary blade, a pedestal adjacent the knife, a casing disposed on the pedestal, a set screw adjustably securing the casing, and an adjustable guard plate carried by the pedestal. 105

3. A fleshing knife comprising the combination of a rotary blade, a pedestal adjacent the knife, a casing adjustably secured to the pedestal, a bracket disposed on the pedestal, a set screw adapted to hold the bracket, a set 110

screw carried by the bracket, and a guard plate provided with a slot adapted to receive the second set screw.

4. In a fleshing knife, the combination comprising a base plate, a rotary knife supported by the base plate, a pedestal on the base plate, a slotted plate on the pedestal, a casing carried by the slotted plate and disposed around the knife, a bracket disposed on the plate, and a guard plate carried by the bracket.

5. A fleshing knife comprising the combination of a rotary blade, a tubular casing surrounding said knife and spaced therefrom, a beveled edge on said casing adapted to guide the hide to be treated, and means for adjusting said tubular casing toward or from the cutting edge of the knife.

6. A fleshing knife comprising the combination of a rotary blade, a tubular casing surrounding the same and spaced therefrom, means for adjusting said casing toward or from the cutting edge of the knife, a guard

plate mounted adjacent the cutting edge of the aforesaid rotary knife, means for adjusting said guard plate relatively to the cutting edge of the knife, a segmental guide on said guard plate, and means for adjusting said segmental guide both horizontally and laterally relatively to the guard plate.

7. A fleshing knife comprising the combination of a rotary blade, a pedestal adjacent the blade, a guard plate adjustably mounted on said pedestal, a segmental guide plate mounted on said guard plate to have both horizontal and lateral adjustment relatively to the guard plate, and means for adjusting said guard plate and the segmental guide thereon relatively to the aforesaid rotary blade.

In witness whereof I have hereunto set my hand in the presence of two witnesses.

LAURENT RUPP.
